Primary Examiner — John Windmuller*Assistant Examiner* — John R Yeh(74) *Attorney, Agent, or Firm* — Shumaker, Loop & Kendrick, LLP(57) **CLAIM**

We claim the ornamental design for a power mop, as shown and described.

DESCRIPTION

FIG. 1 is a front perspective view of a first side of a power mop;

FIG. 2 is a perspective view of a second side thereof;
FIG. 3 is a broken-away perspective view of the power mop;
FIG. 4 is an elevation view of the first side of power mop of FIG. 1;

FIG. 5 is an elevation view of the second side thereof;
FIG. 6 is an enlarged broken-away side view of FIG. 3;
FIG. 7 is a front elevation view of the power mop of FIG. 1; and,
FIG. 8 is an enlarged broken-away front elevation view of the power mop of FIG. 3.

The mop is shown broken away for ease of disclosure only.
